UNITED STATES PATENT OFFICE.

HUGO ISRINGHAUS, OF BARMEN, GERMANY.

BUTTON-MAKING MACHINE.

Application filed July 7, 1924, Serial No. 724,730, and in Germany July 9, 1923.

In the manufacture of metal buttons it has been proposed to stamp from two strips of sheet metal, conducted through the machine on opposite sides thereof, the upper and lower part respectively of the metal button, to put one part upon the other, and to assemble the two parts by flanging the one part. The machines which have been used hitherto for this purpose possess certain inconveniences. For instance, each strip of sheet metal is worked by its own ram comprising its own tools, the stamped parts being put together at another place so that the machine is of large size and expensive and the buttons are not produced with desired accuracy. The machines commonly used are special machines for the metal button industry and the several elements of the machines, machine frame, ram and the like, are constructed only for this special purpose.

In contradistinction thereto this invention relates to a device which avoids the inconveniences mentioned and permits the adoption, without essential alterations, of any eccentric press for the production of metal buttons. This is of the greatest importance as it is thus possible to use any existing eccentric presses for the production of buttons and to use the same eccentric presses at any time for the production of other articles.

This result is attained according to the present invention by bringing the strips of sheet metal as close together as possible and to work the same by means of one and the same tool operated from the one ram of the press, this same tool serving for assembling the two parts of the button. The arrangement for the feeding of the strips of sheet metal is especially advantageous and adapted to the above mentioned conditions.

An embodiment of the invention is shown, by way of example, on the accompanying drawing, in which:

Fig. 1 shows the machine partly in vertical longitudinal section.

Fig. 2 is a plan view of the same.

Fig. 3 is a sectional view through the punch for stamping the upper part.

Fig. 4 is a sectional view through the lower part of the punch.

Fig. 5 is a sectional view of the punch for assembling the upper and lower portions of the button.

According to the present invention the two strips of sheet metal 1, 2, from which the top

and bottom parts respectively are formed, are brought together as closely as possible to be conducted in the well known manner through the machine parallel to one another. As the sheet metal strips are close together they can be worked by a common or single punching device. This device consists of a bed 3 for the die plate 4 and a revolving disk 5, a punching plate 6 comprising two rows of punches 7 and 8 for the shaping of the parts of the button and a separate punch 9 designed to assemble the top part with the bottom part all of the punches being guided by guideways or apertures 4^a in the stationary plate 4^b. The last punch of row 7 carries a drawing device 7^b. This common device is operated preferably by the usual rams of an ordinary double acting eccentric press with outer or cutting ram and inner or cupping ram, the rows of punches 7 and 8 being controlled by the cutting ram and a part of the extreme punch of row 7, e. g. the drawing tool 7^b, the extreme punch of row 8 and the punch 9 being controlled by the cupping ram. With this object in view the punching plate 6 is fixed to a cutting ram and a punch plate 6^a, fixed on the cupping ram, carries the drawing tool.

Instead of a double action press a single action eccentric press may be used, the ram of which operates the rows of punches 7 and 8 and, at the same time, through the intermediary of a lever transmission or the like, the drawing tool 7^b, the extreme punch 8 and the punch on the down stroke 9. It is essential that the revolving disk forms a part of the die for the punches. It is mounted on the die bed 3 so as to be revolvable about a bolt 12 and advanced at each movement of the ram for one division in the well known manner by means of a spring-controlled pawl 13 of a reciprocating carriage 14. Spring-controlled sleeves 15 and stationary bolts 16 are arranged in the revolving disk 5 to form together the moulds for the top part and the bottom part of the button.

While the strip 1 of sheet metal is travelling through the press in the direction of the arrow 17 the first two punches 7 effect in the usual manner the shaping of the top part, viz. the hollow pressing, stamping and punching, the last punch 7 consisting of a cutting tool 7^a and a drawing tool 7^b acts to force the shaped top part into the die 4.

whereupon, for the completion of the cup-shaped part, it is drawn through this die into the revolving disk.

The shaping of the bottom part is carried

8 out in a similar manner, the last punch 8 cutting the bottom part, forcing it through the die 4 and inserting it into a finished top part which, located in a cavity of the revolving disk, is brought under said bottom 10 part upon rotation of said revolving disk.

The punch 9 effects at the next following stroke the connection of the top part and bottom part by flanging the edge of the top part over the rim of the bottom part.

15 At the front edge and rear edge of the press table 11 the feeding mechanisms for the sheet metal strips 1 and 2 are mounted by means of brackets 18. The feeding mechanism consists of two sets of rolls, each com-

20 posed of one lower roll 19 and of two upper rolls 20, 21. The lower rolls 19 and 19 are stationarily mounted in the brackets 18 but the upper rolls 20, 21 and 20, 21 are mounted on oscillable bell-crank levers 22. The

25 upper rolls are permanently pressed on the corresponding lower rolls through the action of an adjustable spring 23, but they may be raised, in overcoming the action of the spring, with the aid of a lever 24 through the rotation of an axle 25, for instance simultaneously with the stopping of the press or when the ram is thrown out of gear.

It is essential that the rolls for the two 35 strips of sheet metal have cylindrical bodies of different diameters; the body 26 of the roll 20 is, for instance, of greater diameter than the body 27 of roll 21. The corresponding body 28 of the lower roll 19 is

40 also of greater diameter than the body 29 of the same roll. When the rolls are being operated in the well known manner from the lower roll by means of spur wheels the strip 1 of sheet metal is advanced more

45 rapidly than the strip 2 although there is only one lower roll.

The revolving movement for the conveying rolls is controlled from the main shaft 50 of the press through the intermediary of a rocking lever, pulling pawl or the like.

The operation of the machine is as follows:—

The first punches of the rows 7 and 8 55 shape the top and bottom parts in the strips of sheet metal, the last punch of row 7 inserting the finished top part into a cavity of the revolving disk 5. The last punch of row 8 puts the bottom part on the top part in the preceding cavity and the punch 9 60 unites the two parts to a button in the cavity which is in front of the cavity into which the bottom part is being deposited. At the back stroke of the ram with the punches the 65 feeding rolls are rotated so that they pull forward the strips of sheet metal, the car-

riage 14 being operated at the same time to advance the revolving disk for one division so that the proceeding which has just been described can be repeated.

I claim:—

1. A device for the production of metal buttons by means of an eccentric press from two strips of material conducted through the press parallel to each other, comprising in combination an eccentric press with an 75 outer ram and an inner ram working in said outer ram, a die plate, a revolving disk under said die plate, a feeding device for guiding the strips of material in proximity to each other over the die, a row of punches over 80 each strip of material for shaping the elements of the button, said two rows of punches being connected with the outer ram, a drawing tool arranged in the extreme punch of one row of punches seen in the direction of 85 movement of the strip of material, and an assembling punch for uniting the shaped and punched button elements, said last mentioned two punches being connected with the inner ram said disk being provided with a plurality of circumferentially spaced moulds, 90 said moulds being adapted to cooperate with said drawing tools and said assembling punch and to move the partially formed elements to said assembling punch. 95

2. A device for the production of metal buttons by means of an eccentric press from two strips of material conducted through the press parallel to each other, comprising in combination an eccentric press with an outer ram and an inner ram working in said outer ram, a die plate, a revolving disk under said die plate, a feeding device for guiding the strips of material in proximity to each other over the die, a row of punches over each 100 strip of material for shaping the elements of the button, the one row of punches shaping and punching the top parts, the other row of punches shaping and punching the bottom parts of the buttons, said two rows of 105 punches being connected with the outer ram, a drawing tool arranged in the extreme punch of one row of punches seen in the direction of movement of the strip of material, and an assembling punch for uniting 110 the shaped and punched button elements, said last mentioned two punches being connected with the inner ram, a plate above the die common to all the punches designed to guide said punches, a spring-controlled 115 drawing pawl operated at every working stroke of the rams and feeding the revolving disk, said revolving disk being provided with moulds spaced a distance apart which is equal to the lateral distance between the 120 two rows of punches, so that for each stroke of the revolving disk a mould is in alignment with the last punch of each row in the direction in which the strip of material 125 moves and under the assembling punch. 130

3. A device for the production of metal buttons by means of an eccentric press from two strips of material conducted through the press parallel to each other, comprising in combination an eccentric press with an outer ram and an inner ram working in said outer ram, a die plate, a revolving disk, two upper rolls and a lower roll for guiding the strips of material over said die in proximity to each other said lower roll serving for both strips of material at the same time said upper rolls being of different diameter for each strip of material, a common bearing for said upper rolls, means for raising and lowering said bearing of the upper rolls, a row of punches over each strip of material for shaping the elements of the button, the one row of punches shaping and punching the top parts of the buttons the other row of punches shaping and punching the bottom parts of the buttons, said two rows of punches being connected with the outer ram, a drawing tool arranged in the extreme punch of one row of punches seen in the direction of movement of the strip of material, an assembling punch for uniting the shaped and punched button elements said last mentioned two punches being connected with the inner ram, a plate above the die common to all the punches and designed to guide said punches, a spring-controlled drawing pawl operated at every working stroke of the rams and feeding the revolving disk, spring controlled sleeves in the revolving disk spaced at a distance which is equal to the lateral distance of the rows of punches so that a sleeve is in alignment with the last punch of each row in the direction in which the strip of material moves and another sleeve under the assembling punch, and bolts in said sleeves, said bolts resting upon said die plate.

In testimony whereof I affix my signature.

HUGO ISRINGHAUS.
